UNITED STATES PATENT OFFICE.

ADOLPH ROSNER, OF BRIDGEPORT, CONNECTICUT, ASSIGNOR TO THE "LOCOMOBILE" COMPANY OF AMERICA, OF NEW YORK, N. Y., A CORPORATION OF WEST VIRGINIA.

INTERNAL-COMBUSTION ENGINE.

1,254,852.

Specification of Letters Patent. Patented Jan. 29, 1918.

Application filed September 27, 1911. Serial No. 651,508.

To all whom it may concern:
Be it known that I, ADOLPH ROSNER, a subject of the Emperor of Austria-Hungary, and a resident of Bridgeport, in the county of Fairfield and State of Connecticut, have invented an Improvement in Internal-Combustion Engines, of which the following description, in connection with the accompanying drawings, is a specification, like characters on the drawings representing like parts.

This invention relates to internal combustion engines and particularly to the means for controlling the admission of fuel to the cylinder and the exhaust of the waste gases therefrom.

In carrying out my invention I preferably make use of slide valves. The valves as herein disclosed, however, are so designed and disposed that an extremely high degree of compression can be readily attained while, at the same time, the valves are simple in construction and operation and are free from the difficulties of lubrication, overheating and other troubles to which valves of this class have heretofore been subjected.

The invention will be best understood by reference to the following description when taken in connection with the accompanying illustration of one specific embodiment thereof, while its scope will be more particularly pointed out in the appended claims.

In the drawings,—

Figure 1 is a transverse sectional elevation taken through a cylinder of an engine equipped with one form of my invention;

Fig. 2 is a detail in perspective, showing the operating connection for one of the slide valves; and

Figs. 3, 4, 5 and 6 are sectional elevations, partly diagrammatic, showing the pistons and valves in different positions.

Referring to the drawings, and particularly to the embodiment of the invention there shown, the engine there illustrated is provided with a fixed main cylinder 1, supported upon the crank casing 2. The piston 3 is provided, connected by the rod 4 to the crank 5 and crank shaft 6. The working space of the cylinder, or that through which the piston travels, is surrounded by the water jacket 7 and the piston slides in direct contact with the water jacketed walls of the fixed cylinder. The rear end of the

cylinder is closed by the cylinder head 8, which is bolted or otherwise fixedly secured to the top end of the cylinder, forming preferably a gas tight joint and a gas tight closure for the end of the cylinder. The cylinder head has the portion 9 which projects into the rear end of the cylinder, the projecting portion being of lesser diameter than the diameter of the cylinder providing thereat an annular space 10 between the cylinder and the reentrant walls of the head. The cylinder head has the centrally arranged spark plug 11 and is provided also with the water jacket 12.

At the rear of the cylinder, beyond the working space thereof and in close approximation to the projecting portion of the cylinder head, are provided the oppositely disposed admission and exhaust ports 13 and 14, respectively. While these ports might be otherwise located, they are preferably formed directly in the walls of the cylinder bore itself and as indicated in dotted lines extend each part way around the cylinder.

In the described embodiment of the invention the ports 13 and 14 are controlled by independently movable slide valves 15 and 16, respectively. While the valves might consist of flat plates or have other than a curvilinear shape, for convenience in construction as well as efficient operation each valve preferably comprises an arc-shaped but non-cylindrical segmental plate, having a curvature corresponding to the curvature of the cylinder bore, so that it is adapted to seat thereagainst.

These valve plates or slides are moved independently up and down by means to be fully described so that their ends which in their lowermost positions terminate short of the piston and the working space of the cylinder, are alternately projected each over its respective port to close the same and withdrawn therefrom to open the port. The valve slides at their inner faces are exposed to the pressure of the gas contained in the cylinder so that they are automatically seated during the compression and working strokes of the piston, the high pressure exerted radially outward against the valves, holding them effectively each against its seat, preventing all leakage at the ports.

To move the valves independently and in properly timed relation actuating devices

are provided, having connection with the valves through openings 17 and 18 formed in the cylinder walls and in the seat over which the valves slide. In the openings 17 and 18 there are pivoted the actuating levers 19 and 20, respectively, shown in perspective in Fig. 2. These are connected to the valves at their outer sides or faces, each by means of a trunnion block 21, seated between lugs 22 projecting outwardly from the valves, the block being spanned by and jointed to the forked ends of the lever.

The openings 17 and 18 being formed in the cylinder and the valves being pressed automatically thereagainst by the pressure within the cylinder space, all leakage is prevented through the openings in the same manner as it is through the ports 13 and 14 when the latter are closed.

20 To actuate the valves the levers 19 and 20 are jointed respectively to the push rods 23 and 24, the latter being connected at their lower ends to the cam rolls 25 and 26 which bear respectively against the actuating cams 27 and 28 on the cam shafts 29 and 30. These cam shafts are driven through gears 31 and 32, meshing with the pinion 33 on the crank shaft, at one-half the speed of the crank shaft. Each cam is provided with 30 one depression which, when brought beneath the cam roll, permits its respective valve to move back into the annular space and open its respective port under the pressure of a valve opening spring, such opening movement therefore taking place once for each two double strokes of the piston.

It will be observed that the cam is effective for positively closing and maintaining the valve closed during compression and 40 firing, while spring pressure is utilized for opening the valve at the appropriate time. In the illustrated form of engine the spring pressure is provided by the main springs 34 and 35, which encircle the push rods 23 and 24, respectively, and press the cam rolls down against the edges of the cams 27 and 28. The push rods and associated parts are housed in by the protecting casings 36 and 37. To supplement the pressure of the 45 springs 34 and 35, as well as to take up lost motion in the actuating connections of the valves, auxiliary springs 38 and 39 are utilized to assist in opening the valves. These springs are seated exteriorly the cylinder head 8, being protected by the caps 40 and 41. Each spring is under compression and presses upwardly against a collar 42 carried by the plunger rod 43, the latter passing through the flange of the cylinder head and having its opposite end threaded to one of the lugs 22. When the 50 depression of the cam passes under the cam roll the auxiliary spring adds its pressure to that of the spring 34 and assists in lifting the valve to an open position.

It will be seen that the slide valves, being separated segments, tend to expand or press outwardly under pressure in the explosion chamber. This causes the valves automatically to seat, their resistance to leakage being thereby automatically increased as the pressure of compression or during the working stroke increases. I have found that this pressure is ample to seat the valves and prevent all leakage with a very small area of 75 the valve exposed, and that if too great an area be exposed to the pressure of the explosion chamber trouble may be experienced in moving the valves. In the present form of engine the valves are required to be 80 moved under pressure only near the end of the working stroke, when the pressure is relatively low. To reduce the working pressure against the valves I have, however, arranged them so that preferably an intense 85 pressure is only applied to a relatively small area of the valve, and herein only to that portion of the slide which is required for closing its port and which projects below the end of the cylinder head.

To this end the segments are each in the form of a half sleeve, with the ends meeting, and are given a close fit in the annular space between the cylinder and the cylinder head. Preferably spring rings 44 and 45 are provided in the walls of the cylinder head, these rings being preferably in the form of packing rings, so that the leakage of high pressure fluid to the upper end of the annular space 10 is prevented. These rings also assist in seating the valves against the walls of the cylinder. Furthermore, I have provided the inner faces of the slides, or those engaging with the walls of the cylinder head, with a substantially uniform surface, so that no pockets are provided for the accumulation of pressure fluid, which might leak past the rings from the explosion space and increase the seating pressure of the valves thereat. The connecting lugs 22 for the actuating levers 19 and 20 being placed exteriorly the sleeves, the inner surfaces of the valves fit the cylinder head closely and the leakage and accumulation of pressure fluid, or at all events high pressure fluid, is thereby substantially eliminated.

Referring to Figs. 3 to 6, inclusive, the operation of the valves will be readily apparent. In Fig. 3 the piston is shown during its admission or suction stroke, the admission valve 15 having been retracted into the annular space and having opened the admission port 13 to the cylinder. The exhaust valve has been previously closed and is still maintained closed by its cam 28.

The conditions which pertain during the compression stroke are represented in Fig. 4. The piston is here shown as having started on the compression stroke, the ad-

mission valve 15 having been previously closed by its cam 27, and the exhaust valve being still maintained closed by its cam 28. Under these conditions the increasing compression within the cylinder increasingly presses the valves against their respective seats, so that as the compression increases so also does the resistance to leakage at and about the valves.

5 10 In Fig. 5 the conditions at the commencement of the working stroke are represented, the piston having started on its second forward movement, and both the valves being still maintained closed by their respective

15 cams.

10 In Fig. 6 the piston is shown as having completed its working stroke and as starting on the return or exhaust stroke, the exhaust valve 16 having been permitted 20 to open by its cam at the commencement of the stroke.

15 The valves may be given a very short stroke, herein the equivalent only of the port opening plus the necessary lap, and 25 through the use of the cams as actuating agents may be moved each at such an appropriate time as gives the most effectively timed port opening for admission and exhaust. Thus, during suction stroke, the admission valve can be opened almost instantly after the commencement of the admission stroke and remain open until a little after the completion of the stroke. On the other hand, the exhaust valve may be 30 opened near the very close of the working stroke and can be kept open until the completion of the exhaust stroke of the piston. By modifying the shape of the cams the precise timing of the valves can be independently varied as may be desired and 35 preferably I so set the cams that the exhaust valve is not closed until a few degrees after the completion of the exhaust stroke of the piston and not until the admission valve has started to open, so that 40 there is a slight interval during which both valves are opened permitting a momentary scavenging action.

45 The opening and closing movements of the valves in each case are effected very rapidly by means of the cams. This adds materially to the effectiveness of the admission, compression, working, and exhaust strokes.

50 55 The cam-operated movement of the valves and the short travel required produces a minimum of wear. It will be observed moreover that the valves are only in motion when the internal pressure is slight, periods of compression and firing occurring 60 when the valves are stationary. This not only reduces the frictional wear of the valves but also the power required to move them and provides conditions which assist 65 in preventing leakage.

The valves as herein shown are preferably located at the rear of the working space of the cylinder and out of contact with the piston, this placing them out of the direct path of heat conduction or dispersion which 70 takes place from the working cylinder space through the cylinder walls to the water jacket. The slide valves therefore are not only themselves out of the direct path of heat which must be dissipated through the 75 cylinder walls and that intense heat which tends to interfere with their effective operation is avoided, but the cooling of the cylinder is much more effectively carried on where the heat does not have to traverse the 80 valves themselves interposed between the piston and the cylinder walls.

85 It will be observed that with the valves located having the major portion of each within the annular space between the cylinder head and the cylinder they are not only protected against the access of pressure to their inner faces but are shielded by the projecting cylinder head from the intense heat 90 of the combustion chamber during the working stroke, the only portions of the valves which are thus exposed being the short projecting ends which cover the ports.

95 While the valves might be arranged upon seats not constituting a part of the cylinder bore, preferably as herein shown they are seated in a continuation of the cylinder bore, being however in a non-concentric or non-overlapping relation to the piston.

100 It will be understood that the terms "front," "rear," "top" and "bottom" as applied to the engine and its cylinder are merely terms of description applied to the specific drawings herein annexed to facilitate a more ready understanding of them, 105 and have no significance as applied to the generic principles of my invention, various embodiments of which may be made wherein the relation of the parts thus referred to may be reversed or variously altered.

110 While I have herein shown and described for purposes of illustration one specific form of the invention, it is to be understood that the latter is not limited to the precise construction of features disclosed nor to the 115 form or relative arrangements of parts nor to the particular type of engine described, but that extensive modifications may be made in the illustrated embodiment of the invention without departing from the spirit 120 thereof.

Claims:

1. In an internal combustion engine, the combination with a cylinder having a port, a cylinder head, an arc-shaped slide valve 125 at the rear end of the piston working in the space between the head and the cylinder and having a portion adapted to be projected therefrom to cover said port, the major portion of the valve contained with the space 130

21
between the cylinder head and the cylinder being protected from the pressure of the explosion space.

2. In an internal combustion engine, the combination of a cylinder, a cylinder head having an inwardly projecting portion, a slide valve working between the cylinder head and the cylinder and presenting a substantially smooth interior to the walls 10 of the head, said valve having a portion adapted to be projected beyond the cylinder head to close the cylinder port.

3. In an internal combustion engine the combination with a cylinder having admission and exhaust ports, a cylinder head having a portion projecting into the cylinder, arc-shaped slide valves closely fitting the space between the cylinder head and the cylinder but adapted to be projected beyond 20 the cylinder head, each to close its port, and means for preventing the access of high pressure to the sides of the valves facing the cylinder head.

4. An internal combustion engine having 25 a cylinder, a piston, a cylinder port, an internally projecting cylinder head, and a segmental arc-shaped slide valve presenting a substantially smooth face in sliding contact with said cylinder head and adapted to be 30 projected beyond the same to close the port.

5. In an internal combustion engine the combination of a cylinder having admission and exhaust ports, independent arc-shaped slide valves at the rear end of the piston 35 adapted to open and close said ports, and a cylinder head having a portion projecting into said cylinder and protecting the inner faces of said slide valves from the access of an excessive seating pressure.

40 6. In an internal combustion engine, the combination with a cylinder having admis-

sion and exhaust ports, a piston, independent arc-shaped slide valves adapted to open and close said ports and automatically seated by the pressure of the gas contained within 45 the cylinder space, a cylinder head having a portion projecting into said cylinder and protecting the inner faces of said slide valves from the access of an excessive seating pressure, and means for moving the valves having connections to the outer side of the valve through an opening in the wall on which 50 the valve seats.

7. In an internal combustion engine, the combination of a cylinder having a port, a slide valve plate adapted to open and close said port, said plate being seated by the pressure of the gas contained within the cylinder space, means for protecting the major portion of said valve from the access of an 60 excessive seating pressure, and operating connections for moving said valve connected thereto through an opening in the wall on which the valve seats.

8. An internal combustion engine having 65 a cylinder, a piston, a cylinder port, an internally projecting cylinder head, a segmental, arc-shaped slide valve presenting a substantially smooth face in sliding contact with 70 said head and adapted to be projected beyond the same to close the port, and operating connections for moving the valve connected thereto through an opening in the cylinder wall on which the valve seats.

In testimony whereof, I have signed my name to this specification, in the presence of 75 two subscribing witnesses.

ADOLPH ROSNER.
